UNITED STATES PATENT OFFICE.

ERWIN R. STOEKLE, OF MILWAUKEE, WISCONSIN, ASSIGNOR TO THE CUTLER-HAMMER MFG. CO., OF MILWAUKEE, WISCONSIN, A CORPORATION OF WISCONSIN.

THERMALLY-CONTROLLED CIRCUIT INTERRUPTER.

Application filed February 14, 1920. Serial No. 358,601.

To all whom it may concern:

Be it known that I, ERWIN R. STOEKLE, a citizen of the United States, residing at Milwaukee, in the county of Milwaukee and

5 State of Wisconsin, have invented new and useful Improvements in Thermally-Controlled Circuit Interrupters, of which the following is a full, clear, concise, and exact description, reference being had to the accompanying drawing, forming a part of this specification.

This invention relates to thermally controlled circuit interrupters adapted to use in various relations.

10 One object of the invention is to provide a simple, efficient and reliable circuit interrupter of such character which may be used to both break and re-establish circuit without renewal of parts and which may be made to so function repeatedly without deterioration 20 of its conductive parts or other impairment of its efficiency.

Another object is to provide a circuit interrupter of such character which may be made exceedingly sensitive and which may be calibrated and adjusted to meet widely varying conditions.

Another object is to provide a thermally controlled circuit interrupter wherein circuit is interrupted between liquid surfaces by pressure on the liquid and in a manner to avoid the contaminating conditions obtaining where circuit is interrupted between solid conductors or a fluid and a solid conductor.

Another object is to provide a thermally controlled circuit interrupter utilizing a fluid conductor which is controlled by variations in thermal conditions in such a manner as to insure quick interruption of circuit between the fluid surfaces.

Another object is to provide a thermally controlled circuit interrupter which may be readily designed and adjusted to re-establish circuit automatically or to require manual resetting as may be desired.

Other objects and advantages will herein-after appear.

According to the present invention it is proposed to employ a conductor which at working temperatures is in a liquid state and to utilize a fluid functioning in response to

thermal changes to divide such liquid conductor for interruption of circuit, such fluid preferably being the product of vaporization 55 of a quantity of such liquid conductor.

In the accompanying drawing wherein are illustrated certain of the various embodiments which the invention may assume in practice,

60 Figure 1 is a diagrammatic illustration of a preferred construction;

Fig. 2 is a similar illustration of a slightly modified construction; while,

Fig. 3 is a similar view illustrating 65 another slightly modified construction.

Referring to Fig. 1 of the drawing, the same illustrates an hermetically tight container 4 composed of insulating and heat resistive material and comprising an enlarged bulb 5 having an axially aligned and restricted tubular extension 6 therebelow. Electrodes 7 and 8 are sealed within the outer ends of said bulb and said extension respectively and arranged to penetrate material distances toward one another within the container, said electrodes being normally electrically connected by a quantity of vaporizable liquid conductor, preferably mercury 9, filling said extension and rising an 80 appreciable distance within the bulb. The remaining space within the container is preferably evacuated prior to sealing, to reduce the hydrostatic pressure upon the mercury column and also for removal of any 85 gaseous matter which might react unfavorably upon the exposed conductive parts during operation. This feature, however, is not absolutely essential and on the other hand, such space might optionally be filled 90 with an electrically inert and non-oxidizing gas, or might even be left open to the atmosphere.

Said tubular extension is provided with an interiorly enlarged portion 10 to include 95 an increased bulk of mercury, said enlarged portion being preferably located at a material distance below the bulb 5. A heating element 11 is arranged exteriorly of the container adjacent said increased bulk of mercury for supplying heat thereto.

In practice heat may be supplied to the element 11 from any convenient or desired source, and upon application of a moderate

degree of heat thereto the adjacent body of mercury is not vaporized to an appreciable extent whereas any slight vaporization which may occur is counteracted by condensation within the bulb. However, upon temporary application of heat above a predetermined value, or upon prolonged application of a lesser degree of heat, said body of mercury becomes heated to a temperature at which 10 rapid vaporization takes place. When such temperature is reached, a quantity of vapor is at once formed within the enlarged portion 10 of the passage whereas the expansive force so liberated serves to displace upwardly the liquid mercury located above the entrapped vapor. Moreover, as such body of liquid mercury rises, the length of its vertical component decreases very rapidly, the inner diameter of the bulb being materially 20 greater than that of the extension. The hydrostatic pressure upon the entrapped vapor is thus so far reduced that the vapor pressure continues to lift the liquid mercury and finally expels the same from the extension. 25 The foregoing action occurs in practice with much rapidity and obviously results in sudden interruption of the controlled circuit between mercury surfaces and in the absence of air or other oxidizing agent, the sole intervening substance being mercury vapor. And since such vapor is incapable of maintaining electrical conductivity for moderate current and voltage values, interruption of 30 the controlled circuit, assuming such moderate values, is accomplished without material arcing or other undesirable effect, whereas for higher values the various parts may be specially designed to reduce or eliminate arcing.

40 Following such interruption of the controlled circuit the same may obviously be reclosed through re-establishment of continuity of the mercury column following reflux of mercury within the upper end of the 45 extension 6. The inner diameter of said extension as a whole and particularly at the junction thereof with the bulb 5 is so selected that following cooling of the entrapped vapor approximately to its condensation 50 temperature, the weight of the suspended mercury column is sufficient to overcome both the pressure of such vapor and the capillary action between the mercury and the walls of the container for causing the mercury to flow back within the extension and 55 reunite with that retained in the lower portion thereof for automatic resetting of the device.

Fig. 2 similarly illustrates a container 60 comprising a bulb 5^a and an extension 6^a, the latter being arranged at an angle to the vertical and the former being arranged with its major axis substantially horizontal, although in practice said bulb may be arranged in alignment with the inclined extension.

Electrodes 7^a and 8^a penetrate the walls of said container and extend appreciable distances therewithin, the electrode 7^a being bent downwardly to dip within a body 9^a of mercury which normally fills the extension 70 and the lower portion of the bulb as in the construction aforescribed.

In this construction, moreover, the electrodes are relatively large while the passage within the extension 6^a is tapered and materially contracted near its central portion to render the ohmic resistance and consequent heating effect of the enclosed column of mercury relatively high as compared with that of said electrodes, whereby the heat developed by passage through said column of an electric current in excess of a predetermined value serves to effect vaporization, expansion and discontinuity of said column with consequent interruption of the controlled circuit 80 in the manner described.

The aforescribed inclination of the container serves to decrease the hydrostatic head upon the contracted central portion of the mercury column for facilitating expulsion of the mercury constituting the upper portion of such column and also for reducing the tendency of the mercury to flow back into the passage following such expulsion, while the junction of said passage with the 90 interior of the bulb is particularly designed to increase the capillary action tending to resist reflux of the mercury within said passage.

Such reduction of the hydrostatic pressure and increase in capillary action serves 100 to prevent automatic resetting of the device, while in furtherance of such end the container may be indented at a point 12 corresponding with the junction between the bulb and its extension, said indentation appearing upon the inside of the container as a hump serving partially to separate the mercury within the bulb from that within such extension. The level of mercury within the 110 bulb, is however, maintained sufficiently high to connect the two bodies of mercury on either side of the hump to permit circulation thereof for assisting in recondensation of any vapor liberated at moderate temperatures corresponding with normal values 115 of the current transmitted.

The aforescribed parts, however, are so designed that a slight agitation of the container, following predetermined cooling of 120 the vapor entrapped within the passage, is sufficient to effect return of liquid mercury within said passage for resetting of the device.

The construction illustrated in Fig. 3 is 125 in most respects similar to that last described, the electrodes and the extension being, however, designed to render the device responsive to thermal influences from an extraneous source as in Fig. 1.

In this construction, however, the container as a whole is pivotally mounted for oscillation about a knife edge bearing 13 located therebeneath in proximity to the junction of the bulb and its extension, whereby upon expulsion of mercury from the upper end of the extension the same flows into the bulb causing the same to overbalance the weight upon the opposite side 10 of the knife edge, whereupon the container is adapted to tilt bodily into the dotted line position, thus effecting a wide interval between the separated bodies of mercury and effectively providing against automatic or accidental resetting of the device. 15 However, resetting may be readily accomplished by manual tilting of the container to its full line position, whereupon the mercury is adapted to flow back into the 20 passage for restoring the interrupted connection.

The aforescribed circuit interrupter may be advantageously employed in numerous relations. Thus the same, particularly 25 as embodied in Figs. 1 and 3, may be adapted to actuation through voluntary application of heat to the element 11, or the mercury column may be arranged to be maintained at a temperature equal or proportional 30 to that of a body which is itself heated by current traversing the controlled circuit, thus adapting the device to maintain the temperature of such body substantially constant. Also, said element 11 may comprise an electric heating device which may 35 be either independent of the controlled circuit or associated therewith in any desired or preferred manner. The latter suggested adaptation obviously includes arrangements 40 providing overload protection of the controlled circuit, to which function the construction of Fig. 2 is particularly adapted. Furthermore, each of the foregoing constructions is capable of calibration and adjustment in numerous ways to meet widely 45 varying demands of service, particularly through varying the character, size or relation of the heating element or the angle of inclination of the container, while for particular uses the device may be designed to provide practically any desired special characteristics.

It may be furthermore stated that the various elements aforescribed are capable 50 of recombination in relations other than those stated, thus for example, either the automatically resetting type or the type requiring voluntary resetting may optionally be rendered sensitive either to thermal variations produced by current of the controlled circuit or transmitted from an extraneous source, whereas either of said methods of heating is equally applicable to the fixed or the oscillating type of container.

What I claim as new and desire to secure by Letters Patent is:

1. A thermally controlled circuit interrupter comprising a column of conductive fluid which is liquid at working temperatures, said column having associated means providing for heating the former to effect vaporization of a portion thereof, and means to restrict circulation and thereby prevent free boiling of the liquid fluid under the influence of said former means to thereby provide for sudden and definite interruption of continuity of said column upon vaporization of said portion thereof, said column also having associated means providing for automatic restoration of continuity thereof following such interruption. 75

2. A thermally controlled circuit interrupter comprising a column of conductive fluid which is liquid at working temperatures, said column having external heating means to effect vaporization of a portion thereof, and means to restrict circulation and thereby prevent free boiling of the liquid fluid under the influence of said former means to thereby provide for sudden and definite interruption of continuity of said column upon vaporization of said portion thereof. 80

3. A thermally controlled circuit interrupter comprising a container having a tubular extension provided with an opening, a column of conductive fluid which is liquid at working temperatures to be contained in said extension, said column having a portion to be vaporized by local heating and a relatively constricted portion located between said former portion and said opening to provide, upon vaporization of said former portion for sudden expulsion of a portion of said column from said extension and beyond said opening to thereby effect sudden and wide interruption of continuity of said column. 100

4. A thermally controlled circuit interrupter comprising a container having a depending tubular extension, a column of conductive fluid which is liquid at working temperatures to be contained in said extension, said column having a portion to be vaporized and a constricted portion located above said former portion to provide, upon vaporization of said former portion, for sudden expulsion of the fluid located thereabove to thereby effect sudden and wide interruption of continuity of said column. 110

5. A thermally controlled circuit interrupter comprising a container having a depending tubular extension, a column of conductive fluid which is liquid at working temperatures to be contained in said extension, means for subjecting a portion of said column to externally applied heat for vaporization of such portion of the column subject to a time element to effect expulsion of 120 125 130

the portion of said column located above such vaporized portion for interrupting continuity of said column, the portion of said column to be so heated being relatively 5 enlarged to augment such time element.

6. A thermally controlled circuit interrupter comprising a container having an enlarged upper portion and a relatively reduced depending tubular extension, a column of conductive fluid which is liquid at working temperatures to be contained in said extension, means for subjecting a portion of said column to externally applied heat for vaporization thereof subject to a 10 time element, the portion of said column to be so heated being relatively enlarged to provide for augmenting such time element and said column having a relatively constricted portion located between said enlarged portion thereof and the enlarged portion of said container to provide upon vaporization of said enlarged portion of the column, for sudden expulsion of that portion of the column located thereabove from 15 the extension and within the enlarged portion of the container to thereby effect sudden and wide interruption of continuity of said column.

7. A thermally controlled circuit interrupter comprising a hermetically tight container having an enlarged upper portion and a relatively reduced depending tubular extension, a column of conductive fluid which is liquid at working temperatures to 20 be contained in said extension, said column having a portion to be vaporized by local heating to thereby expel a portion of said column from said extension and into the enlarged portion of said container for interruption of continuity of said column, said extension being in open communication with the interior of the enlarged portion of the container and the parts being proportioned to provide for automatic reflux of 25 liquid fluid into the extension following given reduction in pressure within the extension.

8. A thermally controlled circuit interrupter comprising a hermetically tight container having an enlarged upper portion and a relatively reduced depending tubular extension, a column of conductive fluid which is liquid at working temperatures to be contained in said extension, said column 30 having a portion to be vaporized by local heating to thereby expel a portion of said column from the extension and within the enlarged portion of said container for interruption of continuity of said column, said extension being in open communication with the interior of the enlarged portion of the container and the parts being proportioned to provide for automatic reflux of liquid fluid within the extension following given 35 reduction in pressure therewithin, the inter-

rior of said container being substantially devoid of gas and non-condensing vapor to thereby prevent entrapment of bubbles within said extension upon such reflux of fluid.

70

9. A thermally controlled circuit interrupter comprising a hermetically tight container having an enlarged upper portion and a relatively reduced depending tubular extension, a column of conductive fluid 75 which is liquid at working temperatures to be contained in said extension, means for subjecting a portion of said column to externally applied heat for vaporization thereof subject to a time element, the portion of said column to be so heated being relatively enlarged to provide for increasing such time element, said column having a relatively constricted portion located between said enlarged portion thereof and the enlarged portion of said container to provide, upon vaporization of said enlarged portion of the column, for sudden expulsion of that portion of the column located thereabove out of the extension and into the enlarged portion of the container to thereby effect sudden and definite interruption of continuity of said column, said extension being in open communication with the interior of the enlarged portion of the container and the parts being proportioned to provide for reflux of the liquid fluid into the extension following given reduction in pressure as a result of condensation or escape from such extension of the vaporized portion of such fluid, the interior of said container being substantially devoid of gas and non-condensing vapor to thereby prevent entrapment of bubbles within said extension upon such reflux of fluid.

95

10. A thermally controlled circuit interrupter comprising a hermetically tight container having an enlarged upper portion and a relatively reduced depending tubular extension, a column of conductive fluid which is liquid at working temperatures to be contained in said extension, means for subjecting a portion of said column to externally applied heat for vaporization thereof, the portion of said column to be so heated being relatively enlarged to provide a time element in the vaporizing action, said column having a relatively constricted portion located between said enlarged portion thereof and the enlarged portion of said container to provide, upon vaporization of said enlarged portion of the column, for sudden expulsion of that portion of the column located thereabove out of the extension and into the enlarged portion of the container to thereby effect sudden and definite interruption of continuity of said column, said extension being in open communication with the interior of the enlarged portion of the container, and the parts being proportioned to pro- 105

- vide for delayed reflux of liquid fluid into the extension following reduction in pressure therewith due to condensation or escape from such extension of the vaporized 40
- 5 portion of such fluid the interior of said container being substantially devoid of gas and non-condensing vapor to thereby prevent entrapment of bubbles within said extension upon such reflux of fluid.
- 10 11. A thermally controlled circuit interrupter comprising a hermetically sealed container and a conducting element therein which is fluid at working temperatures and which is subjected to thermal influences for 45
- 15 vaporization to interrupt circuit therethrough and for subsequent condensation of the vaporized portion thereof, said container being substantially devoid of contained gas and non-condensing vapor and enabling 50
- 20 reuniting of all portions of the elements separated upon circuit interruption.
12. A thermally controlled circuit interrupter comprising a hermetically sealed container having therein terminals to be electrically 55
- 25 connected and a conducting element within said container to electrically connect said terminals, said element being fluid at working temperatures and subjected to thermal influences for vaporization of a portion 60
- 30 thereof removed from both terminals to interrupt circuit between the latter, said container being substantially devoid of contained gas and non-condensing vapor and enabling the element to be re-distributed for 65
- 35 re-establishment of circuit following condensation of the vaporized portion of said element and recombination of the latter with the remainder of said element. 70
13. A thermally controlled circuit interrupter comprising a closed container having a main chamber and a depending tubular extension, and a conducting element which is liquid at working temperatures, said element extending from said main chamber into said extension and being subjected to thermal influences for vaporization of a portion thereof within said extension at a distance from said main chamber, said extension having an internal diameter so restricted as to insure expulsion therefrom 75
- of the portion of said liquid element located above the vapor so liberated and to resist reflux of the liquid element therewithin and said main chamber being materially expanded to receive the liquid element so expelled and to reduce the hydrostatic pressure upon the entrapped vapor during such expulsion.
14. A thermally controlled circuit interrupter comprising a closed container having an enlarged main chamber and a depending contracted tubular extension, a conductive element which is liquid at working temperatures enclosed within said container and extending from said main chamber into said extension and external heating means for effecting vaporization of a portion of said element within said extension and at a distance from said main chamber whereby the pressure of the vapor so liberated serves to expel from said extension the portion of said element located above such vapor for interrupting the electrical continuity of said element, said extension being internally enlarged adjacent said heating means. 80

In witness whereof, I have hereunto subscribed my name.

ERWIN R. STOEKLE.
